UNITED STATES PATENT OFFICE

KARL S. HOWARD AND EDWIN C. JACKSON, OF ST. LOUIS, MISSOURI, ASSIGNEES TO
GENERAL STEEL CASTINGS CORPORATION, OF GRANITE CITY, ILLINOIS, A COR-
PORATION OF DELAWARE

CAR UNDERFRAME STRUCTURE

Application filed June 16, 1930. Serial No. 461,477.

Our invention relates to railway rolling stock and consists in a novel railway underframe structure and more particularly in the combination of a fluid reservoir and a fluid 5 brake cylinder with the underframe.

Customarily, reservoirs and brake cylinders have been completed separately from the underframe structure of the vehicle and have been provided with flanges adapted to be attached to brackets secured to the vehicle 10 framing and by which the reservoirs and cylinder bodies themselves have been secured in place. Such fabricated construction requires frequent and detailed inspection to 15 see that the rivets or bolts are tight to insure maintenance of proper assembly.

Attention is directed to our copending application, Serial No. 368,509, filed June 5, 1929, in which we show brake cylinder bodies 20 integral with a locomotive frame.

The main object of our invention is to secure a rigid and permanent relationship between the air reservoir and brake cylinder member on the one hand and the underframe 25 structure and air reservoir and brake cylinder member on the other hand by making the reservoir and cylinder member integral with the underframe or a part thereof.

Another object of our invention is to reduce 30 maintenance attention and delays by making the reservoir and cylinder member integral with the underframe or a part thereof.

Other detail objects of our invention will 35 appear from a reading of the following description of the device with reference to the accompanying drawings of the same.

The reservoir and brake cylinder elements 40 may be formed integrally with the underframe structure by casting or by any combination of the methods of casting, welding, forging, etc.

Figure 1 is a top view of an underframe 45 structure embodying one form of our invention showing a fluid reservoir, and empty and load brake cylinder bodies, each integral with one or more of the transoms of the underframe.

Figure 2 is a side view of the structure 50 shown in Figure 1.

Figure 3 is a longitudinal vertical section taken on the line 3—3 of Figure 1.

Figure 4 is a transverse vertical section taken on the line 4—4 of Figure 1.

Figure 5 is a transverse vertical section taken on the line 5—5 of Figure 1.

Figure 6 is a top view of a modified form of our invention.

Figure 7 is a longitudinal vertical section taken on the line 7—7 of Figure 6.

Figures 8 to 12 are similar sections illustrating modifications.

Figure 13 is a top view of a separate needle beam showing a brake cylinder body mounted integral therewith and embodying another 55 modification of our invention.

Figure 14 is a side view of the structure shown in Figure 13.

Figure 15 is a transverse vertical section taken on the line 15—15 of Figure 14.

Figure 16 is a side view of a cross bearer member having a brake cylinder body integral with a part thereof and embodying another 70 modification of our invention.

Figure 17 is a transverse vertical section taken on the line 17—17 of Figure 16.

In the structure illustrated in the first five figures, the sides of the underframe are indicated at 1, and are integrally connected by spaced transoms 2, 3, 4, 5 and 6, which are 80 integrally connected to parallel longitudinal center sills 7 and 8.

In this form of our invention, the reservoir member 9 and load brake cylinder member 10 comprise a unit which extends between the two transoms 4 and 5 and is integrally connected to those transoms and thereby held in permanent rigid relation with the underframe of the vehicle. The reservoir is usually of cylindrical shape but may be made of 85 oval or any other shape more desirable in the particular structure.

The reservoir 9 and brake cylinder body 10 have a common wall 13 forming the pressure head for the cylinder. The outer end wall 95 of the reservoir is separate from the body and has a brake rigging bracket 14 integral therewith. On the other side of the center sills 7 and 8 the empty brake cylinder body 11 is united with the transom 3. Brake cyl- 100

inder body 11 is shown with a non-pressure head 15 integral therewith.

Mounted on the end of the reservoir member 9 nearer the transom 4 are the change over valve 16 and the triple valve 17.

Connecting the brake cylinders and the reservoir is a system of brake rigging by means of which any approved braking system may be operated by fluid pressure or hand, as is desirable.

In the modification illustrated in Figures 6 and 7, a portion of an underframe structure is shown in which a fluid reservoir 30 and brake cylinder body 31 are formed integral 15 with each other and disposed end to end and united with the transoms 32 and 33. The outer end wall of the reservoir merges with the web of transom 32. Running through the reservoir 30 and welded to the ends thereof is 20 a tube 34 leading from the triple valve 35 through the opposite end 36 of the reservoir also forming the cylinder pressure head.

In the modification illustrated in Figure 8, the reservoir member 40 has one end 41 separable.

In the modification illustrated in Figure 9, the reservoir 50 is like the one shown in Figures 6 and 7 but extends from transom 52 to transom 53 and is integral therewith, the 30 transom webs forming the end walls of the reservoir. In this arrangement we have shown the brake cylinder body 51 as formed separate from the reservoir although attached thereto. Obviously, in this and in 35 other forms of our invention, the brake cylinder could be mounted on a different part of the underframe.

In the modification illustrated in Figure 10, the brake cylinder non-pressure head 61 only is shown integral with the transom 62, the body 60 being formed separately and attached to the transom. No reservoir elements 40 are involved.

In the modification illustrated in Figure 45 11, a vertically disposed cylinder body 70 is shown integral with transom 71 and includes an integral pressure head 72.

In the modification illustrated in Figure 50 12, a vertically disposed cylinder body 80 is shown having separate heads, the non-pressure head 81 being integral with the transom 82.

In the modification illustrated in Figures 55 13, 14 and 15, a separate needle beam 90 is shown integrally suspending a brake cylinder body 91 and non-pressure head 92 integral therewith, a web 93 depending from the top of member 90 to the top of body 91.

In the modification illustrated in Figures 60 16 and 17, a cross bearer 100 is shown having a member 101 with which a brake cylinder body 102 and non-pressure head 103 are integral.

Some features of our invention may be 65 included in any structure in which instead of

the entire reservoir or cylinder body being integral with the underframe as described above, a part of such reservoir or cylinder member or suitable brackets for supporting the reservoir or cylinder member are integral 70 with the underframe.

Other details in the structure of our invention may be modified without departing from the spirit thereof and we contemplate the exclusive use of all modifications that come 75 within the scope of our claims.

We claim:

1. In a railway vehicle underframe, a center sill, a side sill, spaced transoms between said sills, and a fluid brake reservoir body extending between and merging with said transoms and integral therewith.

2. In a railway vehicle underframe, a center sill extending substantially throughout the length of the underframe, a side sill, 85 spaced transoms between said sills, and a fluid containing device located between said sills and extending between said transoms and integral therewith.

3. In a railway vehicle underframe, spaced transoms, a fluid reservoir, and a brake cylinder body, said reservoir and brake cylinder body each being integral with one or more of said transoms and with each other.

4. In a railway vehicle underframe, a center sill, a side sill, transoms between said sills, and a plurality of fluid containing members arranged end to end and integral with said transoms.

5. In a railway vehicle underframe, a center sill, a side sill, transoms between said sills, and a plurality of fluid containing members arranged end to end and integral with each other and with said transoms.

6. In a railway vehicle underframe, a fluid reservoir, and a brake cylinder body, said reservoir and brake cylinder body being integral with each other and with said underframe and disposed end to end and longitudinally of said underframe.

7. In a railway vehicle underframe, spaced transoms, a fluid reservoir and a brake cylinder body, said reservoir and brake cylinder body being integral with each other and with one or more of said transoms and being disposed end to end and longitudinally of said underframe.

8. In a railway vehicle underframe, spaced transoms, a fluid reservoir, a load brake cylinder body and an empty brake cylinder body, 120 said reservoir and brake cylinder bodies each being integral with one or more of said transoms.

9. In a railway vehicle underframe, a fluid reservoir, a fluid brake cylinder body, and a head for said body, all of said parts being integral with each other and with the underframe.

10. In a railway vehicle underframe, a transom, a fluid reservoir, a brake cylinder 130

- body, and a head for said body, said reservoir, brake cylinder body and head being integral with said underframe and with said transom.
11. In a railway vehicle underframe, longitudinal sills, transom having a continuous vertical web between said sills, and a fluid reservoir integral with said transom and below the top thereof and extending above and below the lower portion of said web. 70
12. In a railway vehicle underframe, longitudinal sills, spaced transoms of substantial depth and each including a vertical web continuous between said sills, and a fluid reservoir integral with and extending between said transoms and located below the tops of said transoms and projecting below the same. 75
13. In a railway vehicle underframe, spaced transoms, a fluid reservoir, and a brake cylinder body, said reservoir and brake cylinder body being integral with each other and with said transoms and disposed end to end of each other and projecting below said transoms. 80
14. In a railway vehicle underframe, an integral structure comprising a center sill extending substantially throughout the length of the underframe and an air reservoir at the side thereof. 85
15. In a railway vehicle underframe, a center sill extending substantially throughout the length of the underframe and an air reservoir integral with said sill and positioned between said sill and the side of the underframe. 90
16. In a railway vehicle underframe, a center sill extending substantially throughout the length of the underframe, a side sill spaced therefrom, and an air reservoir integral with said sills and positioned between them. 95
17. In a railway vehicle underframe, spaced transoms, a fluid reservoir, a triple valve, and a brake cylinder body, said reservoir being integral with one or more of said transoms, one of the walls of said reservoir being integral with the rest of the reservoir and serving as a head for said cylinder body, and a pipe extending through said reservoir and into said triple valve and said brake cylinder body. 100
18. In a railway vehicle underframe, spaced transoms, a fluid reservoir, a triple valve, and a brake cylinder body, said reservoir and said brake cylinder body being integral with each other and with one or more of said transoms, and a pipe extending through said reservoir and into said triple valve and said brake cylinder body. 110
19. In a railway vehicle underframe, a transom, a fluid reservoir and a brake cylinder, said fluid reservoir being integral with said transom, and said brake cylinder being disposed at the end of said fluid reservoir and integral therewith. 115
20. In a railway vehicle underframe, a transom, a fluid reservoir and a brake cylinder body, said brake cylinder body being disposed at the end of said reservoir and integral therewith, and said reservoir extending below and integral with said transom. 70
21. In a railway vehicle underframe, an integral structure comprising a center sill and an air reservoir and a brake cylinder body. 75
22. In a railway vehicle underframe, a center sill and an air reservoir and brake cylinder body integral with said sill and positioned between said sill and the side of the underframe. 80
23. In a railway vehicle underframe, a center sill, a side sill spaced therefrom, and an air reservoir and brake cylinder body integral with said sills and positioned between them. 85
24. In a railway vehicle underframe, an integral structure comprising a center sill and an air reservoir and brake cylinder head. 90
25. In a railway vehicle underframe, a center sill and an air reservoir and brake cylinder head integral with said sill and positioned between said sill and the side of the underframe. 95
26. In a railway vehicle underframe, a center sill, a side sill spaced therefrom, and an air reservoir and brake cylinder head integral with said sills and positioned between them. 100
